CUTTING ATTACHMENT FOR SEWING MACHINES

William Stuart Peppler, Glen Rock, Pa., assignor of one-half to Allen Spangler, Philadelphia, Pa.

Application May 8, 1937, Serial No. 141,523

2 Claims. (Cl. 164—17.5)

This invention is an attachment for sewing machines and is in the form of a cutter for use in connection with sewing machines for cutting stitched strips into suitable lengths to be used 5 for shoulder straps, belt loops, etc., and the invention together with its objects and advantages, will be best understood from a study of the following description, taken in connection with the accompanying drawings, wherein:

10 Figure 1 is an elevational view of the head portion of a sewing machine having my attachment associated therewith, and

Figure 2 is an end elevational view showing the attachment.

15 Figure 3 is a sectional view showing a conventional type of feed mechanism for the machine.

Referring to the drawings by reference numerals, it will be seen that 5 indicates the head of a lock-stitch sewing machine suitably mounted on 20 a base 1 and including among other parts the usual presser foot 2, needle 3, main shaft 4, which latter carries the usual thread take-up wheel 6, hand wheel 16, and driving pulley 8.

In accordance with the present invention, there 25 is suitably mounted on the base 1, a substantially U-shaped frame 9, the legs 10 of which at their upper ends are provided with bearings 11 in which is journaled a shaft 12.

On one end of the shaft 12 there is provided a 30 pulley 13 over which is trained a belt 13' that is also adapted to be trained over a pulley 7, as shown, and mounted on shaft 4 for driving the shaft 12 from the main shaft 4 of the sewing machine.

35 The shaft 12 is provided for operating the vertically movable pivotal blade 14 of a cutter indicated generally by the reference numeral 15 and which also includes a fixed or stationary blade 14'.

40 In the present instance, I have shown the cutter 15 mounted rearwardly of the presser foot 2 and transversely to the line of travel of the strip as the latter is being stitched.

A trip arm 17 is pivoted at one end as at 18 to 45 a suitable part of the head 5 and is normally urged to swing vertically upwardly through the medium of a suitably provided spring 19.

The free end of the trip arm 17 is arranged in 50 the path of a roller 20 provided on a gear 22 mounted on a shaft 23 suitably journaled in a bearing 24 on one of the legs 10 of the frame 9. Intermediate its ends the trip arm 17 is connected through the medium of a link 25 with the blade 14 of the cutter 15 so that, on each revolution of the gear 22 arm 17 will be tripped in a

manner to cause the blade 14 to coact with the blade 14' of the cutter 15 for cutting the stitched strip transversely thereof.

The gear 22 is in constant mesh with a pinion gear 26 provided on one end of the shaft 12. Thus, it will be seen that drive will be transmitted from the shaft 4 through the pulley belt 13' to the shaft 12 to revolve the gear 22 to thereby operate the cutter 15 for cutting the stitched strip into lengths, and by using different sizes of 10 pulleys 13 and 8, gear 22 will be caused to revolve at the desired speed for operating the cutter 15 to cut the stitched strip into long or short lengths as may be found desirable.

Further in accordance with the present invention I suitably mount on one of the legs 10 of frame 9 a counter 27 that includes among other parts a crank arm 28 normally urged in one direction through the medium of a suitably provided spring 29. For operating the crank arm 20 28 once for each revolution of gear wheel 22 there is provided on the gear wheel a second roller 30 that engages the crank arm 28 for swinging the latter against the action of spring 29 to operate the counter so that each time the cutter 15 is operated the counter 27 will be operated to the end that the one operating the machine may keep track of the number of pieces of lengths into which the strip is cut.

For directing the stitched strip to the cutter 15 as the strip passes under the presser foot 2, there is provided a tubular guide member 31 mounted at an incline as shown in Figure 2 intermediate the presser foot 2 and the cutter 15. Thus it will be seen that the tubular guide 31 is so arranged as to direct the strip between the blades of the cutter 15 so that the strip may be cut into lengths in the manner just described.

It will be also understood that the device may be used for cutting into suitable lengths strips which have been previously stitched, and of course where the strips to be cut have been previously stitched the machine with the cutting attachment applied thereto will of course be without thread, the sewing machine then serving merely to engage the length into which the strip is to be cut.

In Figure 3 I have illustrated a conventional type of feed mechanism for the machine which 50 it is believed will be readily understood by those skilled in the art and since the structure shown therein forms no part of the present invention it is not believed necessary to describe the same in detail.

Having just described the invention, what is claimed as new is:

- 5 1. A cutting attachment for sewing machines comprising a U-shaped frame supported in upright position rearwardly of the machine, one end of the frame being adjacent the drive end of the machine and the other end of the frame being adjacent the needle end of the machine, a shaft journaled in the upper end of the frame, a belt-driven pulley secured to one end of the shaft and operatively connected with the drive end of the machine, a pinion gear secured to the opposite end of the shaft, a gear journaled on the frame operatively engaged by the pinion, a pin 10 projecting from the last named gear and a cutting mechanism adjacent the needle end of the machine and comprising a stationary blade, a movable blade pivoted at one end to the stationary blade and a pivoted trip arm mounted above 15 and connected to the free end of the movable blade, said trip arm being disposed in the path of said pin for actuating the movable blade upon rotation of said gear.
- 10 2. A cutting attachment for sewing machines comprising a U-shaped frame supported in up-
- 15
- 20
- 25

right position rearwardly of the machine, one end of the frame being adjacent the drive end of the machine and the other end of the frame being adjacent the needle end of the machine, a shaft journaled in the upper end of the frame, a belt-driven pulley secured to one end of the shaft and operatively connected with the drive end of the machine, a pinion gear secured to the opposite end of the shaft, a gear journaled on the frame operatively engaged by the pinion, a pin 10 projecting from the last named gear and a cutting mechanism adjacent the needle end of the machine and comprising a stationary blade, a movable blade pivoted at one end to the stationary blade and a pivoted trip arm mounted above 15 and connected to the free end of the movable blade, said trip arm being disposed in the path of said pin for actuating the movable blade upon rotation of said gear, the cutting edge of said stationary blade being elevated above the working surface of the needle end of the machine and a guide inclined upwardly from said working surface for directing the work into cutting position relative to the blades.

W. STUART PEPPLER. 25
